S. A. NEIDICH

MAGNETICALLY CONTROLLED CLUTCH

Original Filed June 23, 1925

INVENTOR:
SAMUEL A. NEIDICH,

*By Arthur E. Craig,
Attorney.*

UNITED STATES PATENT OFFICE.

SAMUEL A. NEIDICH, OF EDGEWATER PARK, NEW JERSEY, ASSIGNOR TO NEIDICH PROCESS COMPANY, OF BURLINGTON, NEW JERSEY, A CORPORATION OF NEW JERSEY.

MAGNETICALLY-CONTROLLED CLUTCH.

Original application filed June 23, 1925, Serial No. 39,160. Divided and this application filed December 10, 1925. Serial No. 74,663.

The form of my invention hereinafter described is embodied in a revolution counting and stop mechanism which is claimed in my original application Serial No. 39,160, of which this case is a division.

Said mechanism was designed for use in the manufacture of coated webs, such as carbon paper for billing, duplicating and adding machines. Such fabrics are sold in 10 units of seventy-five lineal feet, but in rolls containing from one to twelve pieces, arranged as parallel plies, in accordance with the kind of machine in which they are to be used, but the length of each piece should 15 be aliquot to such unit length. Therefore, it is highly desirable to have means to limit the cutting of such fabrics to the precise aliquot lengths required, to avoid waste of the materials; and the object and effect of 20 my invention are to provide such means.

As hereinafter described; a convenient embodiment of my invention is accessory to a roller, hereinafter termed the measuring roller, over which such fabric is so progressed as to revolve that roller in accordance with the length of the fabric passed thereover. That accessory device includes an index dial, connected with said roller, by suitable gearing; so that the passage of 25 each such unit length of fabric effects one revolution of said dial. Said dial is arranged as the terminal of one side of an electric circuit and provided with a plurality of concentric circular series of electric contact pins; for instance in the form 30 illustrated, there are twelve such series, respectively including from twelve to one such pins; which are equally spaced in their respective series. Said contact dial is arranged to cooperate with a terminal of the 35 opposite side of said circuit which is conveniently mounted on a slide bar which is adjustably so that said terminal may be presented in registry with any one of the 40 twelve series of pins. Such arrangement renders said accessory device operative to 45 close the electric circuit, by contact of said terminals, any number of times from one to twelve, during each revolution of said

dial, in accordance with the position to 50 which said slide bar is set. In said embodiment of my invention; said electric circuit includes a source of current and an electromagnetic tripping device for a clutch, herein claimed, which is part of the mechanism 55 for progressing said fabric over said measuring roller and between shears so that it may be cut the proper length, when stopped, each time the circuit is closed as aforesaid.

That form of my device also includes convenient means enabling the operator to readily reset the tripping mechanism and clutch to their normal operative positions, and my invention includes the various novel 60 features of construction and arrangement 65 hereinafter more definitely specified.

In said drawings; Fig. I is a diagrammatic elevation of a convenient embodiment of my invention.

Fig. II is a fragmentary vertical sectional 70 view of said dial, and shows the connected position of said electric terminals, corresponding with the position thereof shown in Fig. I.

Fig. III is a fragmentary vertical sec- 75 tional view of said electromagnetic tripping device.

Fig. IV is a fragmentary sectional eleva- 80 tion of said tripping mechanism in cooperative relation with the clutch mechanism 80 and means for resetting the same.

Fig. V is a fragmentary diagrammatic view of some of the parts shown in Fig. III, but on a larger scale.

In said figures; the measuring roller 1 85 is mounted to rotate in a suitable frame of which part is indicated at 2 in Fig. IV. Said roller 1 has the shaft 3 provided with the worm 4 engaged with the worm gear 5 which is rigidly connected with the shaft 6 90 which carries said contact dial 7.

Said dial 7 is arranged as the terminal 95 of one side of an electric circuit with which it is connected by the conductor 8, and is provided with twelve concentric circular series of electric contact pins 9; said series respectively including from twelve to one such pins; which are equally spaced in their

respective series. Each contact pin 9 on said contact dial 7 is arranged to cooperate with the single spring terminal 10 which is arranged as the terminal of the opposite 5 side of said circuit with which it is connected by the conductor 12. Said terminal 10 is conveniently mounted on the slide bar 13 which carries the insulating base 14 to which the upper end of said terminal 10 10 is rigidly connected. Said slide 13 is vertically adjustable and may be secured by the set screw 15, in the bearing 16 which is supported by the machine frame 2, in any convenient manner. It is to be understood 15 that the arrangement is such that said terminal 10 may be presented in registry with any one of the twelve series of pins so that said device is operative to close said electric circuit by contact of said terminals 9 and 10, any number of times from one to twelve, 20 during each revolution of said dial 7, in accordance with the position to which said slide bar 13 is set, in the radial guide bearing 16. As shown in Fig. I, said slide 13 25 is set in its uppermost position, with the upper edge of the bearing 16 in registry with the graduation 12 on said slide, which thus presents said terminal 10 in registry with the twelve terminals 9 in the outermost circular series on said dial 7, so that, as thus 30 adjusted, said device is operative to close said electric circuit by contact of said terminals 9 and 10 twelve times during a single revolution of said dial 7.

35 Said electric circuit, comprising said conductors 8 and 12, includes the source of current 18 and the electromagnetic tripping device 19, as diagrammatically indicated in Fig. I. As indicated in Fig. III; said tripping device 19 comprises the electromagnet 20 which is rigidly mounted in the casing 21, below the armature 22, which is pivotally 40 connected with said casing at its left hand end and conveniently by cone pointed screws 45 in the opposite walls of said casing 21, which are parallel with the plane of section of Fig. III, and said armature is normally upheld in the position shown in Fig. III by a suitable spring 23. In that position; said 50 armature 22 is engaged by the movable latch 25 which is pivoted at its upper end to said casing and has a suitable notch engaging the pin 26, projecting from the tripping lever 27 which is fulcrumed at 28 in said casing 21 and normally upturned to the position shown in Fig. III by the spring 30.

55 In the normal position of the parts shown in Figs. III and IV; said tripping lever 27 extends beneath the hook link 31 which then engages, in its notch 32, the stop projection 34 on the frame 2. Said link 31 is carried by the clutch shifting yoke 35 which is fulcrumed at 36 and operatively connected with the grooved hub 38 of the cone clutch member 39. Said clutch mem-

ber 39 is connected with a suitable electric motor or other means for driving the fabric feed roller 40; which latter may be either directly or indirectly connected with the complementary conical clutch member 41; 70 so that, when the parts are in the position shown in Figs. III and IV; said roller 40 is rotated to progress the fabric 42 which is to be measured as aforesaid.

The construction and arrangement above 75 described are such that whenever said electric circuit is closed to energize said electromagnet 20; said armature 22 is drawn down below the end of said latch 25 thus permitting the latter to be swung to the left by said pin 26 on the tripping lever 27 as said lever 27 is drawn down under tension of said spring 30; thus said tripping lever 27 is tilted by its spring 30 to trip said hook link 31 out of engagement with said projection 32, shown in Fig. IV. Thereupon, said clutch member 39 is axially shifted, to the right in Fig. IV, by the spring 43 connected with the arm 45 on said yoke 35, to thus disconnect said feed roller 40 from its driving mechanism and stop the progression of the fabric 41 through the machine after a predetermined length of such fabric has been passed over said measuring roller 1; such length being variably predetermined 90 by the adjustment of said terminal 10. That is to say; each measured length of the fabric 41 may correspond with from one-twelfth of a revolution of said dial 7, up to a complete revolution thereof. However, the dimensions specified are merely convenient to satisfy the trade demands for the multiple carbon paper rolls aforesaid, and it is obvious that the relations of the measuring roller and dial may be different in 95 accordance with the units of measurement desired.

When said mechanism has been thus automatically electrically tripped and stopped; said armature 22 is held down, in abnormal 100 position, by said latch 25 which has been swung over it by the pin 26 of the tripping lever 27 and, consequently, it is necessary to reset said tripping mechanism to the position shown in Fig. IV; to perform an 105 other measuring operation. I find it convenient to effect such resetting by means of the pedal lever 47, which is normally upheld in the position shown in Fig. IV, by the chain 48 pendent from the spring 49 attached at its upper end to the frame member 2. Said chain 48 has the branch 51 connected at its upper end with the arm 52 of said yoke 35, and is of such length that the first effect of depressing said pedal 47 is 110 to reset said yoke to the position shown in Fig. IV with its hook lever 31 engaged with said frame projection 32, so as to detain the clutch device in position to rotate said roller 1, until the tripping operation aforesaid is 115 120 125 130

repeated. However, said chain 48 has the second branch 54 which is connected by the spring 55, with said tripping lever 27, so that farther downward movement of said 5 pedal 47 resets said tripping mechanism to its initial normal position shown in Fig. III.

Although I have found it convenient to employ my improved magnetically controlled clutch mechanism with the contact dial mechanism aforesaid; it is to be understood that it may be used in conjunction with other means for initiating its operation.

15 Therefore, I do not desire to limit myself to the precise details of construction and arrangement herein set forth, as it is obvious that various modifications may be made therein without departing from the 20 essential features of my invention, as defined in the appended claims.

I claim:

1. In revolution counting and stop mechanism; the combination with a measuring 25 roller; of driving mechanism for said roller, including a clutch mechanism comprising a spring normally tending to release said clutch, and a hook arranged to hold said clutch in operative position until tripped; 30 an electromagnetic tripping lever; and a resetting device, including a pedal lever and a chain extending from said pedal lever; a spring normally upholding said lever by said chain; and two branches of said chain 35 respectively operatively connected with said clutch hook and with said tripping lever; said chain branch connected with said tripping lever being slacker than said branch connected with said hook, and including a 40 spring; whereby downward movement of said pedal lever first resets said clutch and its hook, in operative position, and thereafter resets said tripping lever.

2. In revolution counting and stop mechanism; the combination with a measuring 45 roller; of driving mechanism for said roller, including a clutch mechanism comprising a spring normally tending to release said clutch, and a hook arranged to hold said 50 clutch in operative position until tripped; an electromagnetic tripping lever; and a resetting device, including a flexible connector; two branches of said connector, respectively operatively connected with said 55 clutch hook and with said tripping lever; said branch connected with said tripping lever being slacker than said branch connected with said hook, and including a 60 spring; whereby resetting movement of said connector first resets said clutch and its hook, in operative position, and thereafter resets said tripping lever.

3. In revolution counting and stop mechanism; the combination with a measuring 65 roller; of driving mechanism for said roller,

including a clutch mechanism comprising a spring normally tending to release said clutch, and a hook arranged to hold said clutch in operative position until tripped; a tripping lever; and a resetting device, including a flexible connector; two branches of said connector, respectively operatively connected with said clutch hook and with said tripping lever; said branch connected with said tripping lever including a spring; whereby resetting movement of said connector first resets said clutch and its hook, in operative position, and thereafter resets said tripping lever.

4. The combination with a clutch mechanism comprising a spring normally tending to release said clutch, and a hook arranged to hold said clutch in operative position until tripped; of an electromagnetic tripping lever; and a resetting device, including a pedal lever and a chain extending from said pedal lever; a spring normally upholding said lever by said chain; and two branches of said chain respectively operatively connected with said clutch hook and with said tripping lever; said chain branch connected with said tripping lever being slacker than said branch connected with said hook, and including a spring; whereby downward movement of said pedal lever first resets said clutch and its hook, in operative position, and thereafter resets said tripping lever.

5. The combination with a clutch mechanism comprising a spring normally tending to release said clutch, and a hook arranged to hold said clutch in operative position until tripped; of an electromagnetic tripping lever; and a resetting device, including a flexible connector; two branches of said connector, respectively operatively connected with said clutch hook and with said tripping lever; said branch connected with said tripping lever being slacker than said branch connected with said hook, and including a spring; whereby resetting movement of said connector first resets said clutch and its hook, in operative position, and thereafter resets said tripping lever.

6. The combination with a clutch mechanism comprising a spring normally tending to release said clutch, and a hook arranged to hold said clutch in operative position until tripped; of a tripping lever; and a resetting device, including a flexible connector; two branches of said connector, respectively operatively connected with said clutch hook and with said tripping lever; said branch connected with said tripping lever including a spring; whereby resetting movement of said connector first resets said clutch and its hook, in operative position, and thereafter resets said tripping lever.

7. The combination with a clutch mechanism comprising means normally tending to

release it, and a detent arranged to hold it in operative position until tripped; of movable tripping means; and a resetting device, including a connector having two branches
5 respectively operatively connected with said detent and with said tripping means; whereby resetting movement of said connector

resets said clutch and its detent in operative position, and resets said tripping means.

In testimony whereof, I have hereunto ¹⁰ signed my name at Burlington, New Jersey, this 30th day of November, 1925.

SAMUEL A. NEIDICH.
